STONE LOADING AND TRANSPORTING
DRAG

Richard A. Hendrickson, Waubay, S. Dak.

Application October 20, 1949, Serial No. 122,387

8 Claims. (Cl. 214—65)

1

This invention relates to loading devices and more particularly pertains to a device employing a pair of pivoted and beveled platforms, that is self-loading upon being towed by a tractor or the like.

The primary object of this invention is to pick up objects at one location and to transport them to a remote location for the discharge of the same.

Another important object of this invention is to utilize the towing force of a tractor or the like in raising the object to the position in which it is transported.

A meritorious feature of this invention resides in the provision of a pair of beveled platforms that are pivoted to each other and the novel stop means provided for limiting their relative pivotal movement in the closed position.

Another important feature resides in the combined means for limiting relative pivotal movement of the platforms and for retaining objects upon the platforms.

A final important feature of the present invention to be specifically enumerated herein resides in the ring, cable, and hook arrangement which necessitates a minimum of effort on the part of the operator in arranging the device for either loading or unloading.

These, together with various ancillary features and objects of the invention which will later become apparent as the following description proceeds, are attained by the present invention, a preferred embodiment of which has been illustrated by way of example only in the accompanying drawings, wherein:

Figure 1 is a top plan view of the loading device showing the same in the open position and with the alternative closed position indicated in dotted outline;

Figure 2 is a reduced top plan view of the loading device in the position preparatory to closing and raising an object;

Figure 3 is a top plan view of the loading device illustrating the same in the closed position and indicating in dotted outline an object supported thereon;

Figure 4 is a transverse vertical sectional view taken upon the plane of the section line 4—4 of Figure 1; and,

Figure 5 is a side elevational view of the loading device with an object thereon in position to be transported, with parts broken away and shown in section.

Reference is now made more specifically to the accompanying drawings, wherein like numerals

2

designate similar parts throughout the various views, and in which the loading device is indicated generally by the numeral 10.

The device 10 comprises a pair of platforms 12 and 14 which are pivotally connected at the rear ends by a bar 16 for relative opening and closing movement. The adjacent side edges of the platforms are beveled as at 18 and the bar 16 is pivoted to the platforms 12 and 14 adjacent the beveled edges 18 by means of the pivot bolts 20, pivotal movement of the bar 16 relative to the platform 12 being limited by a stop pin 22 which is received in a notch 24 formed in the end of bar 16.

15 The bar 16, together with the upstanding side rails 26 on the outer side edges of the platforms 12 and 14 and the blocks 28 at the forward end of the platforms, constitute retaining walls upon the platforms for objects that may be supported thereon.

15 The blocks 28, which are secured to the platforms 12 and 14 by suitable fasteners 30, are disposed to abut each other upon closure of the platforms so as to prevent the beveled side edges 18 from sliding upon each other.

20 As shown in Figures 1 and 4 the forward ends of the platforms are bent upwardly, as at 32, and are beveled rearwardly and outwardly adjacent the beveled edges 18, as at 34.

25 Eye loops 36 and 38 are pivotally secured to the forward ends of the platform 12 and 14 by suitable pivots 40, and a ring 42 is secured to the eye 36 by a short length of cable 44. A relatively longer length of cable 46 is secured to the ring 42 and carries a hook 48 at its outer end.

30 The use of the device 10 will be readily understood. The loading device is towed to the loading position by passing the cable 46 through an eye 50 carried on a cross bar 52 of a tractor or suitable towing vehicle, not shown, and the hook 48 is engaged in the ring 42. The device is towed in this manner to the loading position with the device 10 sliding over the ground surface and with the platform 14 trailing as shown in Figure 1.

35 The device 10 is towed to a position relative to the object 54 so as to be adjacent the beveled edges 18. The hook 48 is then removed from the ring 42 and engaged with the eye 38. As will be readily apparent, further towing action

40 by the tractor will cause the platforms to pivot towards each other and the object 54 will be raised upon the inclined planes formed by the beveled edges 18. The closing movement of the platforms will be limited by the pin 22 and the

45 blocks 28, and the object which now rests on the

platforms 12 and 14 will be prevented from falling off thereof by the rails 26, blocks 28, and the bar 16.

After the object 54 has been loaded, the towing action may be continued, in which case the platforms 12 and 14 serve as a sled, until the unloading position is reached, at which point the hook 48 is removed from the eye 38 and engaged with the ring 42. Further towing action will then open the platforms causing the object 54 to fall or slide therefrom, and the device is in condition for a repeat operation.

The present invention, with the exception of the fasteners, may be formed entirely of wood, however, a construction of wood reinforced by iron has been found quite satisfactory, and in fact a heavy sheet of metal secured to the under-surface of the platforms is highly desirable when the device is to be pulled over abrasive materials.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to falling within the scope of the appended claims.

Having described the invention, what is claimed as new is:

1. A loading device comprising a pair of elongated platforms arranged in side-by-side relation and having their adjacent side edges beveled, means hingedly connecting the rear ends of said platforms for opening and closing movement of said platforms relative to each other, a tow cable, and means carried at the forward end of each platform for selectively attaching said tow cable to one or both the forward ends of the platforms.

2. The combination of claim 1, wherein said first means includes a bar overlying and pivotally secured to each of said platforms, and a stop pin on one of said platforms engaging the bar and positively limiting rotation of said bar.

3. The combination of claim 1, including a pair of transverse blocks, each of said blocks being secured to one of said platforms adjacent the forward end thereof, said blocks abutting each other and limiting closing movement of said platforms.

4. The combination of claim 3, wherein the forward portions of the adjacent sides of said platforms are forwardly and outwardly beveled.

5. A loading and transporting device comprising a pair of elongated platforms arranged in side-by-side relation, a transverse bar overlying the platforms adjacent their rear ends, said bar

being pivotally connected to each of said platforms and at one end projecting beyond such pivotal connections, an upstanding stop on one of the platforms to the rear of the bar and engaging such projecting portion of the bar to limit pivotal movement of the latter, a flexible towing element, and means for selectively connecting the towing element to the forward end of one or both of the platforms.

10. 6. The combination of claim 5, wherein the bar is pivoted to the platforms adjacent the adjacent side edges of the latter, and the rear platforms of the adjacent side edges of the platforms being rearwardly divergent.

15. 7. A loading and transporting device comprising a pair of elongated platforms arranged in side-by-side relation, a transverse bar overlying the platforms adjacent their rear ends, said bar being pivotally connected to each of said platforms and at one end projecting beyond such pivotal connections, an upstanding stop on one of the platforms to the rear of the bar and engaging such projecting portion of the bar to limit pivotal movement of the latter, a pair of abutting trans-

20. 25. verse blocks, each of said blocks being secured to the top of one of the platforms adjacent the forward end of the latter for limiting the closing movement of the platforms, the adjacent side edges of the platforms being beveled, a flexible towing element, and means for selectively connecting the towing element to the forward end of one or both of the platforms.

30. 8. A loading and transporting device comprising a pair of elongated platforms arranged in side-by-side relation, a transverse bar overlying the platforms adjacent their rear ends, said bar being pivotally connected to each of said platforms, an elongated flexible towing element having a securing ring intermediate its ends, said element having one end attached to the forward end of one of the platforms, a further ring fixed to the forward end of the other platform, a hook on the free end of the towing element selectively engageable with either of the rings.
